Attorney,

UNITED STATES PATENT OFFICE.

JOHN HARRINGTON, OF COVENTRY, ENGLAND.

FRICITION-CLUTCH.

SPECIFICATION forming part of Letters Patent No. 694,472, dated March 4, 1902.

Application filed March 28, 1900. Serial No. 10,516. (No model.)

To all whom it may concern:

Be it known that I, JOHN HARRINGTON, a subject of the Queen of Great Britain, residing at Coventry, in the county of Warwick, 5 England, have invented certain Improvements in Friction-Clutches, of which the following is a specification.

My invention relates to friction-clutches, and has for its object to combine a reliable grip in one direction and a very free rotation in the opposite direction. I attain this object by the mechanism illustrated in the accompanying drawings, which show a clutch suitable for use in the hub sprocket-ring of 15 a rear-driving safety-bicycle.

Figure I is a side elevation, partly in section. Fig. II is a transverse section of some of the parts. Fig. III is a side elevation of the cam-collar. Fig. IV is a side elevation 20 of the carrier. Fig. V is an elevation of one of the side plates. Figs. VI to VIII show details.

Like numerals indicate like parts throughout the drawings.

25 The cam-collar 2 is provided with inclined surfaces 3 and radial projections 4 and is fixed to or forms part of the hub-body or other part of the machine that is to be driven. Between the inclines 3 and the inner periphery of the 30 outer ring 5 I introduce a number of rollers 6, and in the term "rollers" I include balls, bowls, and the like. The rollers are mounted in a carrier 7, which is provided with radial slots 8 to receive the ends 9 of the rollers, which are preferably turned down for the 35 purpose. The carrier consists of two plates 7 7, lying on either side of the cam-collar 2, which are connected by rivets 10, passing clear of the inclines 3. The projections 4 are 40 bored with holes 11 to receive pins 12, on which are threaded springs 13. The said springs extend beyond the pins 12 and are compressed between the faces of the projections 4 and the respective rivets 10, so that 45 the carrier is impelled in such a direction relatively to the collar that the rollers are always held ready to grip between the inclines 3 and the inner surface of the ring 5. The rollers may be made up of an inner solid spin-

dle covered by sleeves loose thereon, as indicated in dotted lines in Fig. VI.

On rotation of the ring 5 in the direction of the arrow 14 the rollers immediately grip and the cam-collar 2 is carried round with the said ring 5. On the said rotary effort being discontinued the rollers release and rotating on their ends form a roller-bearing for the ring 5. The slots 8 are of such a depth only that the rollers 6 cannot fall entirely within a circle touching the radial extremities, such as 4, of the 60 cam-collar 2'. To avoid any risk of the strain being unequally divided between the rollers, the carrier 7 may be cut up into sections, as indicated in dotted lines in Fig. IV. The collar 2 may be provided with a flange 16, 65 adapted by means of the nuts 17 or other irregularities of surface to be operated by a spanner for attaching and detaching purposes.

What I claim as my invention, and desire 70 to secure by Letters Patent of the United States, is—

1. In a clutch, the combination of an inner part, an outer part, rollers introduced between the said inner and outer parts, inclines 75 for the said rollers, a carrier for the said rollers, and radial slots of limited depth in the said carrier adapted to receive the ends of the said rollers, substantially as and for the purpose set forth.

2. In a clutch, the combination of an inner part, an outer part, rollers introduced between the said inner and outer parts, inclines for the said rollers, a carrier for the said rollers, and springs introduced between the said inner part and the said carrier, substantially 85 as and for the purpose set forth.

3. In a clutch, the combination of an inner part, an outer part, rollers introduced between the said inner and outer parts, inclines for the said rollers, a sectional carrier for the said rollers and springs introduced between the said inner part and the said carrier, substantially 90 as and for the purpose set forth.

JOHN HARRINGTON.
